BATTERY TERMINAL

Olin O. Emery, Jackson, Wyo.

Application November 15, 1934, Serial No. 753,229

2 Claims. (Cl. 173—259)

The present invention relates to an electrical terminal, and more particularly a terminal especially adapted for use in connection with storage batteries.

It is well known that after a terminal has been on a battery post for a considerable period of time, the terminal becomes corroded, it being extremely difficult to remove from the post, resulting in many instances in the damaging of the battery, and it is one of the objects of the present invention to provide a battery terminal which is adjustable to accommodate any size of battery post, and one which will positively engage the binding post providing a positive electrical connection and which can be removed without the necessity of wrenches or causing damage to the battery.

A still further important object of the invention is to provide a battery terminal of this character which is cheap to manufacture, relatively easy to install on a battery post, and easy to remove therefrom.

In the accompanying drawing wherein corresponding reference numerals designate corresponding parts throughout the same,

Figure 1 is a front elevational view of the battery terminal illustrating the position of the operating handle in its upper inoperative position for removing, or placing the terminal on the battery post,

Figure 2 is a front elevational view illustrating the position of the actuating handle for positively and firmly securing the battery terminal on the battery post,

Figure 3 is a top plan view of Figure 1.

Figure 4 is a perspective view of the terminal body, and

Figure 5 is a detail perspective view of the actuating handle and adjustable lever which is pivotally mounted thereto.

In the accompanying drawing wherein for the purpose of illustration there is shown a preferred embodiment of the invention, the reference numeral 6 generally designates the terminal body which includes an annular battery post receiving socket or clamp 8 which is split on one side thereof at 10 as clearly illustrated in Figure 4. The annular clamp 8 is provided with a tapered bore 12 for receiving the tapered battery post 14. To the clamp there is provided a laterally extending integral arm 16 having a bore therein for the reception of the conductor 18.

As clearly illustrated in Figure 4 adjacent the free end of the annular clamp 8 there is provided a laterally extending pin 20 having on the

outer end thereof a shoulder 22. Similarly adjacent the clamp an actuating arm 24 is pivotally mounted to the laterally extending arm 16 through the medium of the transverse pin 26.

Intermediate the ends of the actuating arm 24 there is swivelly mounted on the outer side thereof a nut 30 into which there is adjustably threaded the lever 32. As clearly illustrated the lever 32 is provided with an integral flattened end portion 34 having a centrally disposed aperture 10 36 for receiving the pin 20 of the annular gripping jaw.

On the outer side, adjacent the free end of the laterally extending arm 16 there is provided a stop member 38 which is received in the recess 15 40 in the lowermost locking position of the actuating arm 24.

As clearly illustrated in Figure 1 the annular gripping jaw or clamp 8 is placed over the battery post 14 and by virtue of the slit 10 therein the jaw 20 is adapted to receive battery posts of substantially any size. The lever 32 is then screw-threaded in the nut 30 and the free apertured end 34 placed on the pin 20 between the shoulder and the clamp. Upon a downward pressing of the actuating arm 24, the movable free end of the clamp jaw 8 is drawn toward the stationary free end thereof causing the clamp to tightly and closely embrace the binding post 14 effecting a positive electrical connection therebetween. It is to be noted in the event that it is desired to provide a tighter joint, or to use the terminal for different size binding posts, this may be accomplished by removing the apertured end 34 of the lever 32 from its pin 20 and screwing the arm in or out of 35 the swivelly mounted nut 30.

Attention is invited to the relative position of the pins 20 and 26 and the stop member 38. The pins 20 and 26 being on substantially the longitudinal axis of the battery terminal, while the 40 swivelly mounted nut 30 and the stop member 38 in the lowermost locking position of the arm 24 are below the longitudinal axis, so that in the locking position of the arm 24 the free end of the lever 32 lies below the longitudinal axis to the end that the lever 32 tends to rotate the actuating arm 24 and maintains the same in its lower locking position.

While there is shown for the purpose of illustration a preferred embodiment of the invention, it is to be understood that it is capable of various modifications and changes without departing from the spirit and scope thereof, and it is intended, therefore, that only such limitations shall be im- 50 55

posed thereon as are indicated in the prior art or in the appended claims.

What is claimed is:—

- 5 1. A storage battery terminal comprising a split clamping jaw having a tapered battery post receiving bore therein, an integral conductor receiving arm on said jaw, a pivotally mounted actuating handle on said arm, a laterally extending pin on the free end of said clamping jaw provided on the outer end thereof with a shoulder, a screw threaded nut pivotally mounted on said handle, a lever, one end of said lever being apertured and removably secured on said pin, the other end having screw threads thereon for adjustable screw threaded reception in said nut.
- 10 2. A storage battery terminal comprising an an-

nular split clamping jaw, an integral conductor receiving arm on said jaw, an actuating handle pivotally mounted at one end to said conductor receiving arm, a laterally extending pin adjacent the free end of said clamping jaw having an integral shoulder on the outer end thereof, a nut swivelly mounted intermediate the ends of said actuating handle below the point of pivotal connection of the handle, a screw-threaded lever having an aperture in one end thereof removably secured on said laterally extending pin, the other end being adjustably received in the swivelly mounted nut, and a stop member on said conductor receiving arm for said actuating handle.
